CLAIM

The ornamental design for a display screen with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

1. Display screen with graphical user interface

1.0 : Front

The parts indicated by means of broken lines in the reproduction are not part of the claimed design; the parts indicated by means of broken lines, showing the telephone as well as the display screen, are depicted for environmental illustration only and are not part of the design for which protection is claimed.

1 Claim, 1 Drawing Sheet
(1 of 1 Drawing Sheet(s) Filed in Color)
